UNITED STATES PATENT OFFICE

2,671,993

CONCAVE GRINDER

Samuel P. Jones, Utica, and Ralph W. Richards,
West Winfield, N. Y., assignors to Utica Drop
Forge & Tool Corporation, a corporation of
New York

Application September 18, 1952, Serial No. 310,242

1 Claim. (Cl. 51—141)

1

This invention relates to surface grinding machines in general, and relates more specifically to grinding and polishing true concave surfaces to specific size tolerances.

An object of this invention is to provide apparatus for removing surface metal on a concave surface to close tolerances.

Another object of this invention is to reduce inaccurate grinding caused by gradual tool and die wear.

Other objects and a fuller understanding of the invention may be had by referring to the following description and claim, taken in conjunction with the accompanying drawings, in which:

Figure 1 is a schematic illustration of a conventional belt grinding and polishing machine adapted by the provisions of this invention to accurately remove the surface of concave workpieces over long periods of production; and

Figure 2 is a section taken along the line 2—2 of Figure 1, but with the shoe and workpiece closed into work relationship.

In Figure 1 of the drawings the grinding machine embodying the principles of this invention is illustrated diagrammatically. The grinding machine comprises an endless belt 10 running in a closed path about a drive wheel 11 and an idler wheel 12. An endless abrasive belt 13 runs in a closed endless path about a guide wheel 14 and a guide wheel 15. The grinding machine is provided with ways 18, which are vertical in the particular type of machine illustrated. A carriage 19 operates in a vertical reciprocal path guided by the ways 18. Mechanism is provided for moving the carriage 19 in either direction on the ways, but the driving mechanism is conventional and may be varied as desired for hand operation or automatic power feed. Accordingly, the carriage driving mechanism is not illustrated in the drawings.

The drive belt 10 passes over the top of the wheels 14 and 15, and provides a driving action for the endless abrasive belt by the frictional contact with the abrasive belt. There is no direct mechanical drive of either of the wheels 14 and 15, and accordingly the endless belt 13 can be stalled if excessive friction occurs.

The endless abrasive belt 13 is guided over two idler wheels 21 and 22 and passes around the carriage 19. Usually, prior to this invention, a fixed shoe member is provided on the carriage 19 to act as a pressing shoe to force the abrasive belt into a concave workpiece. According to this invention, there has been provided a roller shoe

2

25 carried by the carriage 19. The roller shoe 25 can best be observed in Figure 2 of the drawings. The workpiece, which is referred to by reference character 27, may be any concave piece, but is illustrated as an airfoil blade having the concave surface thereof tapered. This invention provides the only known method for obtaining good internal grinding of a concave tapered surface. The roller shoe 25 is provided in conical tapered form. However, the bearings which support the roller shoe on the carriage 19 are adapted to hold the bottom surface of the shoe 25 substantially level. Therefore, the use of tapered shoe 25 does not require particular change of idler wheels 21 and 22 from standard practice wherein a stationary shoe is employed. The use of a cylindrical roller shoe 29 will not require any change of the standard idler wheels 21 and 22, either.

20 A base fixture 20 is provided to removably hold a workpiece fixture 26 with the workpiece 27 clamped therein. The workpiece fixture is preferably held in a horizontal level position under the carriage 19. In Figure 1 of the drawings 25 there is illustrated in dotted lines the path of the abrasive belt 13 whenever the carriage 19 is forced downwardly to bring the roller shoe into the cavity of the workpiece. The full lines illustrate the upper position of the carriage 19. The workpiece is changed when the carriage is in the upper position. Figure 2 of the drawings illustrates the carriage in the lower, or work position, wherein the grinding surface of the belt is brought into contact with the workpiece.

Because lowering and raising of the carriage 35 19 will cause the belt 13 to tighten about the wheels 14 and 15, the wheel 14 has been mounted on a pivot support arm 16 held taut by a spring 17. Therefore, as the carriage 19 is lowered, the wheel 14 can move inwardly towards the carriage, and as the carriage is raised, the wheel 14 can swing back to a position removed from the carriage and take up the excess belt.

By the provision of the roller shoe of this invention, particularly in the tapered form illustrated in the drawing, excessive guide shoe wear has been practically eliminated and internal grinding of concave surfaces is readily accomplished even when tapered in form. With fixed guide shoes as provided by the prior art, wear of the belt upon the guide shoe quickly caused a slight change in the contour of the guide shoe which resulted in airfoil surfaces not quite true. With modern jet propulsion aircraft depending 50 more and more on close tolerances in production,

the advantage of the roller shoe 25 will become readily apparent.

Although the invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

A grinding machine for grinding curved surfaces, comprising, an endless abrasive belt, first and second roller guide means, a roller pressure shoe, said first and second roller guide means and said pressure shoe positioned with the axis thereof laterally spaced, second and third roller guide means laterally spaced and elevated with respect to said first and second roller guide means, said abrasive belt passing over and around the second and third roller guide means, over said first and second guide means and under said roller pressure shoe in a closed loop, shiftable mounting means for one of said second and third roller 25 guide means, means to move the pressure shoe

in a vertical reciprocable path to drive the abrasive belt against a workpiece, said shiftable mounting for said roller guide means taking up the slack of said abrasive belt, first and second drive roller guide means, an endless drive belt looped around said first and second drive roller guide means and passing against the tops of said second and third roller guide means, and drive means for said endless drive belt, said drive belt imparting a slippable drive to said abrasive belt by frictional contact.
